UNITED STATES PATENT OFFICE.

JAMES FRANTZ, OF ROANOKE, VIRGINIA, ASSIGNOR TO WHITE AMERICAN LOCOMOTIVE SANDER COMPANY, INC., OF ROANOKE, VIRGINIA, A CORPORATION OF VIRGINIA.

LOCOMOTIVE SANDER.

Application filed November 7, 1922. Serial No. 599,591.

To all whom it may concern:

Be it known that I, JAMES FRANTZ, a citizen of the United States, residing at Roanoke, in the county of Roanoke and State 5 of Virginia, have invented certain new and useful Improvements in Locomotive Sanders; and I do hereby declare the following to be a full, clear, and exact description of the invention, such as will enable others 10 skilled in the art to which it appertains to make and use the same.

This invention relates to a sander primarily adapted for use with locomotives. The principal object of the invention, generally stated, is to provide a pneumatic or 15 fluid pressure sander having a valve arrangement whereby the amount of sand delivered by the sander is within the control of the engineer.

Another object of the invention is to provide a sander and valve mechanism therefor whereby there will be provided a heavy flow of sand when needed, a light flow of sand when the train is running under speed, 20 or a combined flow due to the joint action of both heavy and light flows when necessary.

Still another object of the invention is to provide a sander and valve mechanism 30 so arranged as to automatically provide a cleaning flow of compressed air before and after each operation of the sander by an arrangement of the valve mechanism, the valve mechanism also being adapted in various positions to provide a plurality of variations in the amount of sand delivered by the sander, said variations being selectively within the control of the operator.

There are other objects of the invention 40 as will hereinafter appear from a more detailed description of the single embodiment of the device which has been chosen to illustrate the invention, the novel features whereof will be pointed out in the claims 45 at the end of the specification.

Referring to the drawings:

Figure 1 is a view in vertical section of a sander and valve mechanism constructed in accordance with my invention.

Figure 2 is a view in horizontal section 50 of the valve mechanism, parts being broken away to more clearly illustrate the device.

Figure 3 is a view in plan of the operating mechanism for the valve.

While I have illustrated but a single

sander it will be readily apparent to those skilled in the art that in modern locomotives there are four sanders, two on either side of the locomotive, these sanders being respectively adapted to apply sand adjacent 60 the driving wheels of the locomotive in either direction of travel of the same.

Referring now to the drawings, the numeral 1 indicates, generally, a valve casing which is suitably located in convenient 65 reach of the engineer or operator of the locomotive. This casing consists of a base member 2 and a housing member 3, the housing member being bolted or otherwise secured to the base member and there is 70 interposed between the base and housing member a gasket 4 to prevent the escape of the fluid pressure means hereinafter described. The housing member is adapted 75 to form with the base member a valve casing or chamber 5 substantially circular in form and rotatively mounted within this casing or chamber 5 is a valve disk 6, said disk being provided with a single orifice 7 extending therethrough and on its upper 80 face with a pair of ears or lugs 8. Located between the said ears is the squared end 9 of the operating member 10, the latter being provided with a collar 11 adapted to engage the inner face of the top wall of the 85 casing 5 through which the operating member extends. To the outer end of the operating member 10 there is connected an operating handle 12, said operating handle being preferably pivotally connected to the 90 operating member so as to permit a slight rocking movement between the operating handle and the member. The casing 5 is provided at a convenient point with an inlet orifice 13 to which is connected in any 95 suitable manner a pipe 13^a from the fluid pressure reservoir.

In the base member there are provided a plurality of openings 14, 15, 16 and 17 on each side of the center line or the closed 100 position of the operating handle. Each set of openings is adapted to be connected to one or both sanders similarly positioned, that is each set of openings is connected by suitable pipes with both forward sanders 105 and both rear sanders, respectively, if but a single valve is used for the complete sanding equipment. If two valves are utilized, each set of openings is connected to either the forward or rear sander, as desired.

Since these pipes are similar it will only be necessary for a full understanding of the invention to describe in detail the connection between the same and a single sander.

5 The opening 14 is connected by a suitable pipe 14^a to an air passage 18 in the sander casing 19, as will hereinafter be more fully described. The opening 15 is connected by a suitable pipe, as shown in dot and dash 10 lines, with a pipe 20, the latter being conveniently connected to a nozzle 21 which lies adjacent the lower wall of the sander casing 19. The opening 16 is connected by a suitable pipe with a pipe 22, the latter being 15 also connected with an air nozzle 23, which is positioned above the nozzle 21 and within the sander casing 19. The opening 17 is connected by an inverted Y pipe 24 with the pipes leading from the openings 15 and 16, 20 as clearly shown in Figure 1 of the drawings, and hence leads to the pipes 20 and 22 and likewise to the nozzles 21 and 23, respectively.

The sander casing 19 preferably comprises 25 an L-shaped member having a pair of connected chambers or legs 25 and 26, the chamber 25 being adapted to be suitably connected to the sand dome or sand reservoir of the locomotive. The chamber 26 is provided at 30 the opposite end from the air nozzles with a downwardly directed orifice 27 for the escape of sand. The air passage 18 is preferably formed in the upper wall of the chamber 26 and is provided with an opening 28 35 immediately above and in line with the orifice 27 so as to permit the cleaning blast of compressed air from the opening 14 of the valve to clean the orifice 27 and the sand pipe leading therefrom, when desired. Adjacent the orifice 27 there is provided a 40 shoulder 29 which is adapted to entrap the sand within the chamber 26 and to prevent the gravity flow of the sand through the orifice 27. The sand from the sand reservoir 45 filling the chamber 25 and flowing into the chamber 26 normally occupies the position shown in Figure 1 of the drawings.

The sander casing 19 is conveniently provided with a number of screw plugs 30, 31 50 and 32 to permit access to the interior of the casing for cleaning when necessary.

The operation of the device is as follows:

Upon a rotation of the handle 12 from closed position there will be a corresponding 55 rotation of the valve disk 6 and the orifice 7 thereof will come in alignment with the opening 14, whereupon a cleaning blast of compressed air will pass through the port 14, through the air passage 18, through the 60 opening 28, and the orifice 27 to clean out obstructions which may form within the orifice 27 or the pipe leading therefrom. Upon a further rotation of the handle in the same direction, the orifice 7 will leave 65 the port 14 and register with the port 15

whereupon the compressed air will flow through the pipe 20 and the nozzle 21. It is to be observed that the nozzle 21, owing to its position adjacent the lower wall of the chamber 26 and the distance from the 70 surface of the entrapped sand, will cause a large volume of sand to be forced out of the orifice 27, the object of this large flow of sand being to provide a sufficient amount for the starting of the train or for any other 75 condition when a large quantity of sand is needed. A further rotation of the handle 12 in the same direction will bring the orifice 7 of the disk in register with the opening 16, whereupon the flow of air through the 80 pipe 20 will be stopped and the compressed air will flow through the pipe 22 and the nozzle 23 and, owing to the position of the latter at a point adjacent the opposite wall of the casing or chamber 26 and lying nearer 85 the surface of the entrapped sand, a material decrease in the flow of sand from that occasioned by the nozzle 21 will take place. This position of the operating handle is intended when the engine is running and a small 90 amount of sand is needed to compensate for the condition of the track. A further rotation of the handle will bring the port 7 in register with the opening 17, whereupon the compressed air will pass through the inverted Y pipe 24 and into pipes 20 and 21, giving a simultaneous flow through both nozzles 21 and 23 and a correspondingly greater flow than from either of the nozzles 21 or 23, singly. The purpose of this increased flow is for emergency stops when a large amount of sand is necessary. There may be other occasions when the combined flow of sand is desired and the application of this simultaneous flow of both nozzles is 10 not to be limited to such emergency stops.

The top of the valve casing is conveniently provided with a series of V-shaped notches corresponding in number and location to the ports 14, 15, 16 and 17, and into these 11 notches is adapted to seat the spring-pressed plunger 33 carried by the handle 12.

It will be obvious from the foregoing description that the operator of the improved sander device may selectively control the 11 amount of sand passing from the sander to the track as desired to suit various conditions and it is within his option to provide either a light or a heavy or a maximum flow as desired. It will be also apparent that on 12 both the opening and closing movements of the valve mechanism a cleaning blast of air is directed through the orifice 27 so as always to maintain this orifice and the sand delivery pipe open for the passage of sand. By the use of my device the amount of sand used by the engineer is materially reduced and at the same time provision is made for adequate amounts of sand to suit various 13 conditions.

Having thus described my invention, what I claim is:

1. A sander for locomotives, comprising a casing provided with connected chambers arranged at an angle to each other, means formed within one of said chambers adapted to trap the sand therein, a plurality of air nozzles extending into said last named chamber and arranged at different distances from the surface of said entrapped sand, and valve means for admitting compressed air to said nozzles, said last named means being adapted to admit air to either of said nozzles singly or to a plurality of said nozzles simultaneously.
2. A sander for locomotives, comprising a casing having a plurality of connected chambers, a shoulder formed on the wall of one of said chambers to trap the sand therein, said chamber being provided with an outlet orifice adjacent said shoulder, and a plurality of nozzles extending through one of said chambers and into the other, one of said nozzles lying adjacent a wall of said chamber, another of said nozzles lying adjacent the opposite wall of said chamber, and valve means for admitting compressed air to said nozzles.
3. A sander for locomotives comprising a plurality of connected chambers, one of said chambers being connected to a sand reservoir, the other chamber having an orifice for the escape of the sand, a pair of air nozzles extending within said last named chamber, said nozzles being spaced apart and adapted to extend unequal distances within the said chamber, and means for admitting compressed air to said nozzles singly, and means for admitting compressed air to said nozzles simultaneously.
4. A sander for locomotives comprising a casing having connected upright and longi-

tudinally extending chambers, said upright chamber being connected to a sand reservoir, means formed on a wall of said longitudinally extending chamber to limit the gravity flow of the sand, a pair of nozzles extending within said last named chamber, said nozzles having their open ends located at different distances from the surface of the sand within said chamber, and valve means for admitting compressed air to said nozzles either singly or simultaneously.

5. A sander for locomotives comprising a hollow L-shaped casing, one leg of said casing being adapted to be connected to a sand reservoir, the other leg of the casing being provided with an orifice for the escape of sand, a pair of air nozzles extending within said last named leg of said casing and each adapted to lie adjacent opposite walls of said leg, and valve means controlling the admission of compressed air to said nozzles, said valve means being adapted to admit air singly to either of said nozzles and being adapted also to admit air simultaneously to both of said nozzles.

6. A sander for locomotives comprising an L-shaped casing provided with sand inlet and outlet orifices, said casing also being provided with an air passage opening adjacent said outlet orifice, a pair of nozzles extending into said casing and directed toward said outlet orifice, and valve means for controlling the admission of compressed air to said casing, said valve means being adapted in one position to admit air to said air passage and in another position to admit air singly to either of said nozzles, and in a third position to admit air simultaneously to both of said nozzles.

In testimony whereof I affix my signature.

JAMES FRANTZ.
